Lounsbury and Coffey
ATTORNEYS.

UNITED STATES PATENT OFFICE.

PETER BEGHETTI, OF SAN FRANCISCO, CALIFORNIA.

STENCIL.

Application filed December 27, 1922. Serial No. 609,190.

To all whom it may concern:

Be it known that I, PETER BEGHETTI, a subject of the King of Italy, residing at the city and county of San Francisco and State 5 of California, have invented new and useful Improvements in Stencils, of which the following is a specification.

This invention relates to stencils of the changeable letter type, and has for its object 10 to simplify and improve the construction and operation of such a stencil and provide a device in which the letters can be quickly and easily interchanged or replaced.

In carrying out this object I employ a 15 stencil frame adapted to support a plurality of individual stencil plates in various arrangements and combinations. The frame is fitted with a hinged clamping member which may be easily manipulated to clamp the 20 stencil plates in position. The individual plates are so constructed as to permit of easy manipulation.

One form which my invention may assume is exemplified in the following description and illustrated in the accompanying drawings, in which—

Fig. 1 shows a plan view of a stencil embodying my invention.

Fig. 2 shows a cross section of the same. 30 Fig. 3 shows a longitudinal, sectional view thereof.

Referring in detail to the accompanying drawing, I show a stencil frame 10 adapted to serve as a holder for individual plates. 35 This frame is preferably formed of a single piece of sheet metal curled at its edges 11 to afford increased strength and rigidity and bent to form parallel guide members 12 on one of its faces. These guide members assist in positioning the stencil plates and also increase the strength and rigidity of the frame.

Formed in the frame between the guide members 12 are a plurality of rows of rectangular apertures 13, the apertures in each 45 row being separated by cross webs 14. The cross webs in each row are aligned with relation to those of the adjacent row.

For use with each frame I provide a set 50 of individual stencil plates 15, each cut out

to form a letter, numeral or other sign character. These stencil plates are formed with an offset face 16 adapted to seat in the apertures 13 in the frame, the plates being of a size and shape to cover one of the spaces or 55 apertures 13. Each plate has an upstanding flange 17 formed at one of its ends, said flange being adapted to be engaged by the thumb and finger of the operator for convenience in positioning the plates in place. 60 The side edges of the plates are formed with projections 18, which abut when the plates are assembled in rows to prevent overlapping of the plates.

To maintain the plates in position on the 65 frame I provide a clamping member 19 for each row, said clamping member being formed with a rod bent into shape and hinged at one end of the frame, as shown at 20. The opposite end of the clamping member co-operates with a pivoted latch 21, which serves to retain it in position overlying the stencil plates. The clamping member is of such width that one of its sides 70 lies against the inside face of the upstanding flange on the stencil plates, thus securely locking the plates against sidewise movement. The offset face on the plates, being seated within the open space in the frame, 75 will also assist in preventing displacement of 80 the stencil plates.

Various changes in the construction and arrangement of the several parts herein shown and described may be employed without departing from the spirit of my invention as disclosed in the appended claims. 85

Having thus described my invention, what I claim and desire to secure by Letters Patent is:—

1. A stencil comprising a frame formed 90 with a plurality of rows of apertures, a plurality of individual stencil plates adapted to register with said apertures, each plate having an upstanding flange at its end and a U-shaped member pivoted at one end to the 95 frame in line with each row of apertures and adapted to fit within the upstanding flange of the said stencil plates and means for latching the said U-shaped member in position on the frame. 100

2. A stencil comprising a frame formed of a single sheet of metal, said frame being provided with a plurality of spaced apertures arranged in parallel rows, said frame being bent to form a plurality of guide members between the rows of apertures, a set of individual stencil plates adapted to be arranged in registry with the apertures and having offset faces to seat within the said apertures and a clamping member 10 hinged at one end of the frame and arranged above each row of apertures for retaining the stencil plates in position on the frame.

PETER BEGHETTI.
